Specification for Design.

Patented Aug. 8, 1916.

Application filed May 8, 1916. Serial No. 96,247. Term of patent 7 years.

To all whom it may concern:

Be it known that HENRY V. HARTZ, deceased, late a citizen of the United States, residing at Cleveland, in the county of Cuyahoga and State of Ohio, did invent a new, original, and ornamental Design for Boats, of which the following is a specification, reference being had to the accompanying drawing, forming part hereof, wherein—

Figure 1 is a perspective view, and Fig. 2 an end elevation of a boat exhibiting said new design.

I claim:—

The ornamental design for a boat, as shown.

WILLIAM G. METZGER,
Administrator of the estate of Henry V. Hartz, deceased.
